Stanley Meyerson, 1350 Ocean Parkway, Brooklyn, N.Y.

Filed Mar. 15, 1960, Ser. No. 59,751

Term of patent 14 years

(Cl. D45—4)

FIG. 1

FIG. 3

FIG. 1 is a plan view of an expandable link chain for a bracelet, partly expanded, showing my new design;

FIG. 2 is an enlarged longitudinal sectional view taken on line 2—2 of FIG. 1; and

FIG. 3 is an enlarged transverse sectional view taken on line 3—3 of FIG. 1.

The dominant features of my design reside in the portions shown in full lines.

I claim:

The ornamental design for an expandable link chain for a bracelet or the like, as shown and described.
